MOP SQUEEZING ATTACHMENT FOR
MOP PAILS

Edward A. Twerdahl, Evanston, Ill.

Application December 31, 1946, Serial No. 719,601

2 Claims. (Cl. 15—260)

1

The present invention relates to apparatus for mopping floors and the like and more particularly to an improved attachment for a mop pail which may be used in combination with a mop of improved construction to reduce the drudgery ordinarily attendant with this type of work.

Conventional mopping apparatus consists of a string mop and a water pail for containing the mopping liquid, with no facilities being provided for wringing out the mop. This means that in using the apparatus the mop must be wrung out by hand. Various crank operated wringing devices usually adapted for attachment to the mop pail, have been developed and sold commercially to eliminate the hand wringing operation. However, all such devices as well as hand wringing require that the mop user stoop over and either crank the wringing device or twist or squeeze the mop during each mop wringing operation. Hence, conventional methods of mop wringing are laborious and time consuming.

It is an object of the present invention, therefore, to provide improved, simple and low cost mopping apparatus of light easily portable construction which completely obviates the above-described operational disadvantage.

It is another object of the invention to provide improved mopping apparatus which may be easily operated without requiring any stooping or muscular exertion on the part of the mop user during mop wring out operations and without the mop user's hands coming in contact with the cleaning liquid, thus permitting the use of strong detergents or cleaning solvents in the cleaning liquid.

It is a further object of the invention to provide an improved mop squeezing or wringing attachment of low cost construction which may be easily and quickly attached to any mop pail of standard dimensions and is easy to use.

The invention both as to its organization and method of operation, together with further objects and advantages thereof, will best be understood by reference to the following specification taken in connection with the accompanying drawings, in which:

Fig. 1 is an elevational perspective view of an improved mop squeezing attachment characterized by the features of the present invention as attached to a standard mop pail;

Fig. 2 is a view similar to Fig. 1, but illustrating the parts in changed positions;

Fig. 3 is an elevational perspective view of the attachment when detached from the pail; and

2

Fig. 4 is a view partially in section more clearly illustrating the manner in which the attachment may be detachably secured to the rim of a pail.

Referring now to the drawings and more particularly to Figs. 1 and 2 thereof, the present improved mopping apparatus is there illustrated as comprising a standard mop pail 10 and a mop structure of improved construction indicated generally at 11. In brief, the pail 10 is in the form of an open top liquid container of generally round configuration having a beaded flange 12 around the rim thereof.

Preferably, the mop 11 is of the improved form disclosed and claimed in applicant's copending application Serial No. 698,275, filed September 20, 1946. In brief, it comprises a combination support and squeezing plate 13 of rectangular configuration which is adapted to be mounted upon the threaded end of a mop handle 14 by means of a threaded socket element 15 rivet connected to the plate 13 at the upper side thereof. At its underside, the plate 13 is adapted to support a mopping element 16 which preferably is of the synthetic or natural sponge type and may be of any reasonable thickness such, for example, as two inches. In order to secure the mop element to the plate 13, this element is stitched, adhesively bonded or otherwise secured to a flexible textile fabric backing element having free end extensions 17a and 17b, which are adapted to be wrapped around the front and rear edges of the plate 13 and have eyelets respectively provided therein at spaced points therealong. Laces 18 and 19 of the shoe string variety, appropriately threaded back and forth between these eyelets and having their respective ends tied together, may be employed to pull the fabric element taut about the plate 13 and thus fixedly secure the mopping element 16 to this plate. For the purpose of forcing the plate 13 toward the mop squeezing means described below, thereby to expunge cleaning liquid from the mopping element 16, a pair of raised steps 20 and 21 are mounted

upon the plate 13 along the top side thereof. More specifically, these steps are of identical U-shaped configuration and each is provided with laterally extending leg ends rivet connected to the plate 13. Preferably, the two steps are mounted to extend transversely of the long side of the plate 13 and are spaced equidistant from the respective ends thereof on opposite sides of the socket element 15.

In accordance with the present invention, flat rectangular mop squeezing means indicated gen-

erally at 22, are provided to cooperate with the plate 13 in squeezing the mopping element 16 dry after each mopping operation, together with means in the form of a one-piece, resilient wire like element 23 for detachably mounting the mop squeezing means upon the rim of the pail 10 for pivotal movement about one of the long edges thereof. More specifically, the mop squeezing means 22 is in the form of a screen covered frame comprised of a U-shaped member 24 having a cross rod 25 spot welded to the extremities of its legs 24a and 24b, and having the ends of its base 24c detachably held in engagement with the rim of the pail 10 by the element 23 in the manner described below. As shown in Fig. 2 of the drawings, the cross rod 25 is adapted to engage the rim of the pail 10 at the ends thereof when the frame is pivoted to its lowered mop squeezing position and to this end is of greater length than the width of the pail rim at the points of engagement therewith. A heavy wire screen 26 covers the area defined by the four sections 24a, 24b, 24c and 25 of the frame to provide the mop squeezing surface. This screen is fixedly secured to all four sections of the frame as by soldering, welding or the like. Alternatively, the mop squeezing surface may be defined by cross rods spanning the legs 24a and 24b of the frame and spot welded to these legs at spaced points therealong. Regardless of the manner in which the mop squeezing structure is formed, this structure should have openings therethrough of sufficient size to permit free liquid drainage into the pail 10.

Referring now more particularly to the construction of the supporting element 23, this element is illustrated as comprising a U-shaped part 27 adapted to be inserted into the pail 10 and having legs 28 and 29 which terminate in clip portions 30 and 31, respectively. These clip portions are adapted clampingly to embrace the base 24c of the frame member 24 and the beaded rim 12 of a mop pail 10, thereby detachably to mount the mop squeezing means upon the rim of the pail for pivotal movement about the edge thereof defined by the base 24c of the frame member 24. More specifically, the clip portions 30 and 31 embrace the frame member 24 at the corners thereof and have parts 32 and 33, respectively, at the ends thereof which are looped back to engage the frame legs 24a and 24b intermediate the ends of these legs and serve to bias the mop squeezing means to a non-covering position relative to the top of the pail, i. e., to a position extending outward and away from the top of the pail. Preferably, the loop parts 32 and 33 engage the frame legs 24a and 24b, respectively, at the outer sides thereof, thereby to bias the clip portions 30 and 31 of the element 23 into the corners of the frame member 24, and are provided with inturned fingers 32a and 33a which extend under the frame legs 24a and 24b.

For the purpose of normally restraining the mop squeezing means in a raised angular position relative to the pail top against the bias afforded by the loop parts 32 and 33, i. e., in the position illustrated in Fig. 1 of the drawings, a flexible element 34 in the form of a short length of small link chain is provided to connect the base 23a of the element 23 with the screen 26. Preferably the element 34 is connected to the screen 26 at a point on the side of the line passing through the fingers 32a and 33a opposite from the frame base 24c, such that the biasing loops 32 and 33 act to bias the frame base 24c into the clip portions 30 and 31 even when the

attachment is detached from a pail 10. By so doing, the flexible element 34 and the biasing loops 32 and 33 serve to hold all parts of the attachment fully assembled in the manner best illustrated in Fig. 3 of the drawings.

With the components of the attachment fully assembled, the attachment may be mounted upon a mop pail 10 of standard construction by inserting the U-shaped part 27 of the element 23 into the pail and pushing down on the clips 30 and 31 until these clips snap over the beaded rim 12 of the pail. As thus mounted upon the pail, the mop squeezing means is, through the action of the element 34 and the biasing loops 32 and 33, held in a raised angular position relative to the pail top, i. e., in the position shown in Fig. 2 of the drawings. Thus the top of the pail is uncovered sufficiently to permit the mop head to be readily inserted into and withdrawn from the pail. Further, the mop squeezing means is so positioned that the bail of the pail may readily be elevated to carry the pail and attachment from place to place without the mop user's hand bumping against the cross rod 25.

In using the apparatus, the mop head is inserted through the open pail top to submerge the same in the cleaning solution in the pail and is then withdrawn to carry out the desired mopping operation. Each time the mopping element 16 becomes filled with soiled or dirty solution picked up from the floor being cleaned, the mop may be hand manipulated to position the mopping element 16 on the mop squeezing screen 26, following which the mop user may push down on the mop head to pivot the mop squeezing means 22 about the frame base 24c against the action of the biasing loops 32 and 33 until the cross rod 25 rests on the rim of the pail. With the mopping element 16 still positioned on top of the screen 26 in the manner shown in Fig. 2 of the drawings, the user of the mop may place one foot on the steps 20 and 21 and step down on these two steps, thereby to force the plate 13 toward the screen 26, compress the sponge, and thus expunge the soiled or dirty cleaning solution from the mopping element 16. As the liquid flows out of this element, it drains through the openings in the screen 17 back into the pail. After the mopping element is thus squeezed dry, the mop may be lifted, permitting the mop squeezing means 22 to spring back to its elevated position, shown in Fig. 1 of the drawings, under the influence of the biasing loops 32 and 33, thereby to uncover the pail top sufficiently to permit reinsertion of the mop head into the pail.

From the foregoing explanation, it will be understood that the present improved mopping apparatus represents a distinct advance in the art in that it serves completely to obviate one of the foremost disadvantages of conventional mopping equipment. Thus it completely eliminates the necessity for the mop user to stoop over, either for the purpose of carrying out the mopping operation or for the purpose of squeezing out the mopping element when this element becomes soaked with dirty liquid. Moreover, the structure of the attachment is simple in the extreme and all components thereof are capable of being manufactured and assembled through the use of low cost, high speed production methods. Further, the attachment is of very rugged construction such that it will withstand hard usage for an extended period of time.

While one embodiment of the invention has been described, it will be understood that various modifications may be made therein which are

within the true spirit and scope of the invention as defined in the appended claims.

What is claimed as new and desired to be secured by Letters Patent of the United States is:

1. A mop squeezing attachment for a mop pail, including flat mop squeezing means for at least partially covering the open top of a mop pail comprising a frame including means supported from said frame defining openings through which liquid squeezed from a mop may drain into the pail, means for detachably mounting said mop squeezing means upon the rim of a pail for pivotal movement relative to said pail and including a one-piece wire element having an intermediate portion thereof engageable with the inside of said pail and portions adjacent each end thereof defining loops embracing a portion of said frame and also engageable with the rim of said mop pail thereby to provide a fixed pivot for said mop squeezing means when said attachment is associated with said mop pail, the ends of said wire element defining resilient loops engaging said frame and biasing said mop squeezing means about said fixed pivot to a non-covering position relative to the pail top, and a flexible element connecting said mop squeezing means and said intermediate portion of said element to restrain said mop squeezing means in a raised angular position relative to the pail top, thereby normally to uncover the pail top sufficiently to permit insertion of a mop head into the pail, said mop squeezing means being adapted for pivotal movement about said fixed pivot against the action of said resilient loops to its lowered position at least partially covering the pail top, thereby to provide a mop squeezing surface through which liquid squeezed from a mop may drain into the pail.

2. A mop squeezing attachment for a mop pail, comprising flat mop squeezing means for at least partially covering the open top of a mop pail and having openings therethrough through

which liquid squeezed from a mop may drain into the pail, a one-piece resilient wire element provided with a U-shaped part adapted to be inserted into a pail to engage the inside thereof and extensions for detachably engaging the rim of a mop pail and defining a fixed pivot for said mop squeezing means, said wire element including clip portions adjacent the leg extremities of said U-shaped part clampingly embracing a portion of said mop squeezing means to detachably mount said mop squeezing means upon the rim of the pail for pivotal movement about said fixed pivot, said clip portions of said element having resilient loops at their extremities the ends of which engage said mop squeezing means at points spaced from said fixed pivot to bias said mop squeezing means to a non-covering position relative to said pail top, and a flexible element connecting said mop squeezing means and said U-shaped part to restrain said mop squeezing means in a raised angular position relative to the pail top, thereby normally to uncover the pail top sufficiently to permit insertion of a mop head into the pail, said mop squeezing means being adapted for pivotal movement about said fixed pivot against the action of said resilient means to its lowered position at least partially covering the pail top, thereby to provide a mop squeezing surface through which liquid squeezed from a mop may drain into said pail.

EDWARD A. TWERDAHL.
